US0D1071039S

(12) **United States Design Patent** (10) **Patent No.:** **US D1,071,039 S**
(45) **Date of Patent:** **** Apr. 15, 2025**

(54) **WEIGHT**

(71) Applicant: **Richard C. Petek**, Medina, OH (US)

(72) Inventor: **Richard C. Petek**, Medina, OH (US)

(**) Term: **15 Years**

(21) Appl. No.: **29/948,826**

(22) Filed: **Jun. 24, 2024**

Related U.S. Application Data

(63) Continuation of application No. 29/913,642, filed on Oct. 6, 2023, now Pat. No. Des. 1,039,079, which is a continuation of application No. 29/779,933, filed on Apr. 21, 2021, now Pat. No. Des. 1,005,420.

(57) **CLAIM**

The ornamental design for a weight as shown and described.

DESCRIPTION

FIG. 1 is a perspective view of the first embodiment of a weight showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment of a weight showing my new design;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of a third embodiment of a weight showing my new design;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

The broken lines show portions of the design that form no part of the claimed design.

1 Claim, 21 Drawing Sheets
